PLOW

Rudolph J. Altgelt, South Bend, Ind., assignor to
 Oliver Farm Equipment Company, a corpora-
 tion of Delaware

Application February 9, 1939, Serial No. 255,436

4 Claims. (Cl. 97—113)

The present invention relates generally to plows, but more particularly to plow shares and the method of manufacturing the same.

The invention in the present instance is a continuation in part of my copending application Serial No. 157,514 filed August 5, 1937, now Patent No. 2,280,681, granted April 21, 1942, on Plow.

It has become the well established practice in the manufacture of plow shares to process these particular parts through an expensive factory labor procedure. In the manufacture of shares heretofore, either one of the three following procedures has been adopted:

(a) Cast iron chilled shares have been made for the past fifty years in which the material along the cutting edges is chilled in the molding operation so that the cutting edge is substantially harder than the balance of the share. The hardness in this type of share extends a short distance back from the cutting edge while the remaining portion is substantially softer.

(b) The second type of share heretofore used is the forged or plain steel share with its inherent expensive operations to produce.

(c) The third type of plow share heretofore used is the soft center three ply type.

With the above types of steel plow shares, the Brinell test clearly shows that while the hardness of each of these shares varies considerably in different spots, the average share is slightly softer at the cutting edge than on the surface of the share.

In conventional shares heretofore manufactured the forward portion or point of the share extends laterally so as to occupy a width greater than the normal width of the rear portion of the share. The particular configuration that the share has assumed in the past has a distinct disadvantage in that it will not take on a uniform hardness in the tempering operation, but will assume a hardness which varies considerably at different portions of the share so that the conventional share heretofore manufactured is usually softer at the cutting edge than on the surface thereof.

It is therefore one of the primary objects of the present invention not only to overcome the disadvantages hereinbefore pointed out, but to also provide a novel share and method of making the same by means of which the cost of production is so reduced that the cost of replacement will be less than the cost of resharpening the old share and thus make a savings of considerably more than over fifty percent on the present conventional share.

A further object of the invention is to provide a novel, improved and relatively narrow plow share in which a minimum amount of material as possible is used to the best advantage so that the share may be sold at a low price and eliminate the necessity of resharpening a dull share by substituting a new one.

Another object of the invention is to provide a novel and improved plow construction in which the forward end of the landside member is flattened and widened so as to reinforce and strengthen the forward or pointed portion of the share.

These and other objects of the invention are accomplished by providing a construction and a new method of manufacture in the manner hereinafter described and defined in the appended claims.

Referring to the drawing:

Fig. 1 is an end elevational view of my improved plow construction illustrating diagrammatically the manner in which the scouring surface thereof may be ground or polished;

Fig. 2 is a top plan view of my improved plow construction;

Fig. 3 is a fragmentary view showing the manner in which the two beams are rolled together prior to breaking them into sections for making the plow share;

Fig. 4 is a cross sectional view taken on the line 4—4 in Fig. 3;

Fig. 5 is a fragmentary top plan view of one of the beams or bars showing the manner in which the bars are cut for forming the plow shares; and

Fig. 6 is an end view of the finished plow share.

In the present application I have illustrated in the drawing a plow construction which comprises a main standard or base member 10 to which is secured in the usual manner a radius or symmetrically curved mould-board 11. Secured to the other side of the standard 10 is an improved form of landside member 12 which has its forward portion curved and widened as shown at 13. The widening of this forward portion is such that it extends outwardly of the landside member in a direction away from the landside as shown at 14 so as to give greater strength and greater support to the forward point of the plow share. In order to accommodate the laterally extending curved portion 14 of the landside member 12, the standard at this point as indicated by the reference character 15 is curved to be complementary thereto as clearly shown in Fig. 2 of the drawing. In this connection it will also be noted that the lower forward edge as shown at 16 extends parallel to

and in alignment with the lower edge 17 of the standard.

One of the important features of the present invention includes the method of forming the bars or longitudinal edges thereof having formed thereon beads or ribs 18 so that these may be subsequently ground or polished off so as to produce sharp corners and eliminate a seam or spacing which would otherwise be produced at the point of junction between the share and the mouldboard. In other words, it has been found by experience that in the former process of rolling steel bars, especially of high carbon steel, that it was not possible to roll these members without producing rounded corners. These rounded corners leave a spacing on the edges of the share between the share and the mouldboard. Such a spacing will not produce a good scouring surface necessary for efficient plowing. Therefore, in order to eliminate this difficulty or disadvantage and simplify the method of producing an efficient plow share with the minimum of labor, the longitudinal bead or rib permits the share to be fastened to the standard adjacent the mouldboard and during the grinding or polishing operation the bead may be removed so as to produce in effect a seamless plow surface between the share and the mouldboard. This is accomplished without grinding or otherwise finishing the edge of the share which lies contiguous to the mouldboard.

Another important feature of my improved method of producing plow shares includes the indentation or longitudinal V-shaped groove 19 extending between the two longitudinal bars 20 and 21 in the operation of rolling these members. Simultaneously with the rolling of the V-shaped longitudinal grooves 19 the lower surface of these bars are flattened as shown at 22 so that when the bars are broken from one another they break on the longitudinal line of the V-shaped groove 19 forming the cutting edge of the plow share. In this connection it will be noted especially from Fig. 4 of the drawing, that the plow shares when rolled at the steel mills by the operation above described they assume a uniform cross section throughout their entire length so that each share will take on a uniform temper in the tempering operation. With this shape of share, the thinner or cutting edge throughout its length has a uniform hardness while that portion which gradually becomes larger or thicker in cross section assumes a lesser hardness. In other words, the share assumes a hardness which gradually increases from its upper edge to the cutting edge throughout its entire length. The hardness in the tempering operation which the share takes on varies in its width, that is, it is greater at the cutting edge but lesser at the mouldboard edge, but is nevertheless uniform throughout its length. In this connection it will also be observed that the width of the plow share and the amount of material used in producing the same is reduced to a minimum so that the cost of replacement of a new plow share will be less than the cost of sharpening the conventional plow share heretofore used.

In the operation of removing the bead or rib from the longitudinal edge of the plow share 20, the share is fastened to the standard by countersunk bolts 23 and the polishing apparatus diagrammatically illustrated by the reference character 24 in Fig. 1 of the drawing is provided with an abrasive or polishing wheel 25 and is moved over the cylindrical surface of the mould-

board share so as to remove or eliminate the bead and produce in effect a seamless plowing surface which is conducive to efficient plowing.

The cutting edge of the plow share should be in line with the lower surface of the share in order to give the plow "suction" or penetration in its operation of plowing. With the large V-shaped groove rolled on the top of the bar and the flat surface rolled under the V-shaped formation in the rolling operation, the bars may be broken apart on this V-shaped groove and without any further factory operations, that is, grinding or polishing of the cutting edge of the share, the share is ready for use. It will also be observed in this connection that in the rolling operation the flat edge of the bar is rolled at an acute angle to the surface of the share with a longitudinal bead formed on the upper edge of the bar at this point. The primary purpose of this acute angle (instead of a right angle) in the joint between the mouldboard and the share is to hold down the front edge of the mouldboard while the plow base is being polished. The polishing operation heats the mouldboard and causes it to curl up especially when the polishing is done rapidly. The lapping or overhanging of the share on the lower mouldboard edge prevents this.

Summarizing the advantages of my improved plow construction and method of making the same, it will be obvious that by producing a plow share for replacement which will cost less than the cost of sharpening the old plow share, considerable time, money and labor is saved to the operator and more efficient plow structure is produced. It will also be observed that the only grinding or finishing operation required in the share is that of polishing the surface since the share by this new rolling process does not need to be ground on the cutting edge or any other part in order to be prepared for use.

While in the above specification I have described one embodiment which my invention may assume in practice as well as one method of manufacturing the same, it will of course be understood that the same is capable of modification and that modification may be made without departing from the spirit and scope of the invention as expressed in the following claims.

What I claim is my invention and desire to secure by Letters Patent:

- 50 1. A plow construction comprising a standard having its forward end curved outwardly from the landside, a mouldboard secured to said standard, a plow share secured to said standard, a landside member secured to said standard having a forwardly widened point curved laterally and engaging the curved surface of said standard for reinforcing the point of said share.
- 55 2. A plow structure comprising a standard, a mouldboard secured to said standard, a plow share having its cutting edge and mouldboard edge extending parallel with respect to each other, the forward end of said standard being curved away from the landside of said plow structure, a landside member secured to said standard and having its forward end flattened and widened, the forward end of said landside member being curved forwardly and laterally to conform to the curvature of said standard for reinforcing the forward point of said share.
- 60 3. A plow construction comprising a standard, a mouldboard secured to said standard having its lower edge beveled downwardly and forwardly, a plow share secured to said standard having a beveled edge contiguous with and complementary
- 65
- 70
- 75

2,306,996

to the beveled edge of said mouldboard, said share having a point extending forwardly of said standard, said standard having its forward portion curved outwardly from the landside of said plow, a flat landside member secured to said standard and having its forward end flattened and widened and complementary to the curved portion of said standard for reinforcing and strengthening the point of said share.

4. A plow construction comprising a standard

having its forward end diverging in a direction away from the landside, a mouldboard secured to said standard, a plow share secured to said standard, a landside member secured to said standard having a forwardly widened point diverging laterally from and conforming to the diverging portion of said standard for reinforcing the point of said share.

RUDOLPH J. ALTGELT.
